US0D1029993S

(12) **United States Design Patent** (10) **Patent No.:** **US D1,029,993 S**
(45) **Date of Patent:** **** Jun. 4, 2024**

(54) **FAUCET FOR AIRCRAFT**

(71) Applicant: **The Boeing Company**, Chicago, IL (US)

(72) Inventor: **Stephen M. Young**, Los Alamitos, CA (US)

(73) Assignee: **The Boeing Company**, Chicago, IL (US)

(**) Term: **15 Years**

(21) Appl. No.: **29/773,057**

(22) Filed: **Mar. 5, 2021**
